DENTURE

Charles H. Wharton, Seattle, Wash.

Application December 16, 1929
Serial No. 414,295

16 Claims. (CL. 32—4)

This invention relates to lower dentures. Heretofore dentures of this sort have been of integral or unitary form with the result that the provision and maintenance of proper accommodation to the mouth and balancing on the foundation or lower jaw along the entire denture from end to end has been practically impossible. The uni-lateral functioning of a one-piece lower denture also produces objectionable bi-lateral stresses upon the tissues under the denture. For example, in a one-piece denture all movements along the posterior part at either side are accompanied by movements along the posterior part at the opposite side and along the front or anterior part of the denture, with the result that a downward pressure, compressing the tissues under the posterior part at one side produces objectionable stresses upon the tissues along the anterior part and also along the opposite posterior part.

Furthermore, in taking an impression of the lower jaw for a full one-piece lower denture it has been necessary to take a single impression of the entire lower jaw with the result that the tissues along the front or anterior part of the jaw are stressed along with the stressing of the tissues along the posterior parts, whereas the ideal conditions for taking the posterior impressions are that the anterior tissues be at rest and not under stress.

Where the base of a one-piece denture is formed to grip around the mylohyoid ridge the extension of the posterior portions back along the retro-molar region has necessarily been limited in order to permit insertion and removal of the denture.

I have conceived that the objections and disadvantages in a one-piece lower denture can be eliminated by making the lower denture of sectional construction and it is, therefore, the object of this invention to provide a sectionalized lower denture comprising a plurality of denture parts joined together and constituting a full lower denture.

I am aware that partial dentures have been provided with spaced denture parts, adapted for complementary relation with respect to the natural teeth in the mouth, but these are not full dentures and the problems of a full denture are not encountered therewith. Furthermore, the spaced parts of a partial denture have been rigidly or integrally connected to form a unitary or one-piece partial denture or the separate parts have been secured to the natural teeth.

The sectionalized construction which I provide enables the provision and maintenance of better accommodation to the mouth and enables uni-lateral functioning without bi-lateral stress and each posterior part permits of downward pressure independently of the anterior and

opposite posterior part, thereby enabling the compression of the tissue pad under either posterior part without compressing the tissues under the anterior or opposite posterior part. The separate removability of the anterior part permits the posterior portions of the denture to be extended farther back into the retro-molar regions without interfering with the desired freedom of removal and insertion of the denture. The sectionalized construction makes it possible to take the impression of the lower jaw in different sections instead of in a single impression. This enables taking the impressions of the posterior areas under pressure and separately and with the anterior tissues at rest.

It is another and more specific object of the present invention to so take the impression and so construct the sectionalized denture that the masticating pressures on the anterior teeth will be partly taken care of by the posterior parts of the denture on either side so that the posterior parts will begin compression on the posterior tissues before pressure is brought upon the tissues along the anterior parts.

The particular number of parts into which the denture is divided and the particular nature of the joints or connections between the parts may vary widely within the scope of this invention. In the preferred embodiment of the invention the denture is made up in three parts, right and left hand posterior parts carrying the posterior teeth with a separate anterior or front part carrying the six lower anterior teeth. The meeting ends of the parts are preferably on such inclined planes that the intermediate anterior part is carried by the posterior parts, the anterior part being in the form of a wedge between said posterior parts. The joints are adapted to make the sectionalized denture sufficiently rigid in action to permit of stability and to enable the denture to be balanced on the foundation or lower jaw (without wiggling) and these joints or connections may be non-hinged or hinged as desired. The abutting ends of the anterior and posterior parts of the denture are preferably faced to form smooth and properly cooperating surfaces permitting ready adaptability and when in place stability from all movements except downward movement of the posterior parts which are always free for up and down movement but not for lateral movement, being held relatively rigid as to lateral movement when in place.

In order to acquaint those skilled in the art with the construction and operation of the invention, I shall now describe a particular embodiment of the invention in connection with the accompanying drawing in which

Figure 1 is a top plan view of an embodiment of the invention;

Figure 2 is a rear elevational view partially in section taken on the line 2—2 of Figure 1 and showing the foundation or lower jaw in dotted lines;

5 Figure 3 is an enlarged fragmentary top plan view showing on an enlarged scale the particular joint illustrated in Figures 1 and 2 for joining adjacent sections of the denture together; and

10 Figure 4 is a fragmentary detail section taken on the line 4—4 of Figure 3.

Referring to the drawing, the illustrated embodiment of the invention comprises right and left hand lower posterior parts 5 and 7 and an intermediate front or anterior lower part 6 disposed therebetween and constituting with the parts 5 and 7 a full lower denture. The part 5 comprises a base portion 8 carrying the right hand posterior lower teeth 9 and the part 6 comprises a base portion 10 carrying the left hand posterior lower teeth 11. The anterior part 7 comprises a base portion 12 carrying the anterior six lower teeth.

15 The base portions 8 and 10 may be of any suitable or preferred material, gold, rubber, and condensites being now commonly used for this purpose. The teeth 9 and 11 and the lower anterior teeth 13 are rigidly attached to the respective base portions 8, 10 and 12.

20 The bottoms of the base portions 8, 10 and 12 are formed at 15 to conform with the foundation or lower jaw indicated in dotted lines at 16 in Figures 1 and 2, this formation, while continuous around the full denture is sectionalized along the joints between the denture parts and the impression may be taken in separate sections instead of in one impression (as heretofore) which permits taking the impressions of the posterior areas under pressure independently of the anterior area so that the anterior area may be at rest and without any stressing thereof with pressure upon the posterior areas. This permits of pressure upon the posterior areas and enables taking the impressions of the posterior areas without stressing the anterior area and this is one of the advantages of the present invention. Another advantage lies in the better accommodation which may be provided and maintained with the foundation or jaw 16 and in the uni-lateral functioning without bi-lateral stress which the sectionalizing of the full artificial denture permits.

25 As already brought out, each posterior part 5 and 7 is adapted to take downward pressure independently of the other and this enables compression of the tissue pads under either posterior part of the denture without compressing the tissues under the anterior part 6 and without compressing the tissues under the opposite posterior part.

30 The posterior base portions 8 and 10 of the posterior sections 5 and 7 are preferably formed at 17 and 18, respectively, to grip around the mylohyoid ridge indicated more or less illustratively at 20 and the sectionalizing of the denture enables the intermediate anterior section 6 to be separately removed. This permits extending the posterior parts 8 and 10 back farther into the retro-molar regions 21 and 22, respectively without interfering with the desired freedom of removal and insertion of the denture. Heretofore in a full denture of one-piece or unitary construction it has always been necessary to allow the complete denture

35 to be shifted rearwardly so that it may be tilted or cocked up for engagement with and disengagement from the mylohyoid ridge. With a full denture of sectionalized construction this is unnecessary.

40 The sectional construction of the denture also permits accommodation in the denture of stresses under mastication posteriorly without bringing those stresses to the front, or anterior part of the denture.

45 With a full one-piece denture it has, as already brought out, been impossible to take the impression without stresses along the anterior tissues because the stresses of mastication posteriorly have always been transmitted, at least 50 partially, to the front, where not desired.

55 The bases of the base portions 8 and 12 abut endwise at 25 and the bases of the base portions 12 and 10 abut endwise at 26. These abutting ends 25 and 26 are preferably in inclined planes as indicated by the dot and dash lines 27 and 28, the anterior part 6 being disposed between the parts 5 and 7 and preferably constituting a wedge between the bases of the sections 5 and 7. The joints at 25 and 26 are 60 preferably so constructed, that the surfaces of the joints are on such inclined planes and the impressions are preferably so taken that the anterior intermediate part 6 is carried by the posterior parts 5 and 7. This enables taking 65 care of the masticating stresses on the six anterior teeth 13 partially, at least, by the posterior parts 5 and 7 on either side, the stresses being imposed on the posterior tissues before any stresses are brought upon the tissues 70 beneath the anterior section 6 of the denture.

75 The opposite ends of the base of the anterior part 6 are preferably provided with facings 30 and the ends of the posterior parts 5 and 7 which about the opposite ends of the part 6 are 80 preferably provided with facings 31.

85 These facings 30 and 31 are preferably of gold, although any other suitable or preferred material may be employed and they form smooth and properly cooperating inclined surfaces, permitting adaptability along with stability of the parts when in place from all movements except downward movement of the posterior parts, which are always free up and down, but not laterally, the parts being joined 90 and rigidly held against lateral movement by suitable joining means.

95 The joining means may be in the form of a hinge joint or non-hinged joint and may vary widely within the scope of the present invention 100 as already pointed out. The particular joints shown comprise a dowel pin 34, an intermediate vertical dove-tailed tenon 35 and an inner relatively long dove-tail vertical tenon 36, all formed integral with or rigidly secured to the 105 facings 30 and each of the facings 31 has a complementary outer vertical dowel socket 37, an intermediate dove-tail socket 38 and an inner elongated vertical dove-tail socket 39 forming with the pin 34 and tenons 35 and 36 110 and adapted to receive the same as shown in Figure 3 by slipping the intermediate anterior part 6 vertically into place between the parts 5 and 7. This joint or fitting, hinged or not hinged (as shown) makes it possible to make 115 the three-piece lower denture sufficiently rigid in action to permit of great stability and the denture may be effectively balanced on the foundation or lower jaw without wiggling over 120 its entire length.

- The elongation of the inner socket 39 and inner tenon 36 reinforces the denture and provides great strength laterally along the joints between the sections.
5. The facings 30 and 31 may be cemented or otherwise rigidly secured directly to the ends of the denture sections.
- I do not intend to be limited to the precise details shown or described.
10. I claim:—
1. A sectionalized lower denture comprising a plurality of tooth carrying denture parts, and means joining said parts for relative up and down movement in the use of the denture in the mouth, said denture parts supplementing each other around the mylohyoid ridge of the mouth and constituting a full lower denture.
  2. A sectionalized lower denture comprising a plurality of tooth carrying denture parts supplementing each other adjacent the mylohyoid ridge of the mouth and constituting a full lower denture and, joining means holding said parts relatively rigidly against lateral movement and permitting free up and down movement between parts of the denture.
  3. A sectionalized lower denture comprising a plurality of tooth carrying denture parts, means joining said parts for relative up and down movement and holding same against relative lateral movement in use of the denture in the mouth, said parts supplementing each other to constitute a full lower denture, and said parts having bases abutting endwise.
  4. A sectionalized lower denture comprising a plurality of denture parts joined for relative movement and constituting a full lower denture, said parts having bases abutting endwise and inclined and one of said parts being disposed and constituting a wedge between the other parts.
  5. A sectionalized lower denture comprising a plurality of denture parts, each consisting of a denture base and teeth carried thereby, said parts constituting a full artificial lower denture free of anchorage in the gum, and means joining said parts for self-adjustable relative up and down movement after positioning the denture in place in the mouth and in use of the denture in masticating.
  50. 6. A sectionalized lower denture comprising a plurality of denture parts each consisting of a denture base and teeth carried thereby, said parts constituting a full artificial lower denture, and means for joining said parts together and permitting relative up and down movement when in use, said joining means being disposed at the abutting ends of said denture parts.
  60. 7. A sectionalized lower denture comprising a plurality of separable denture parts, means joining said parts together for relative up and down movement when in use, said parts constituting, when joined, a full artificial lower denture and each of said parts having a denture base and teeth carried thereby.
  65. 8. A sectionalized lower denture comprising separable right and left hand posterior denture parts carrying posterior teeth and an anterior denture part carrying anterior teeth disposed between said posterior parts and constituting there-with a full artificial lower denture, and means on said parts whereby the posterior parts transmit masticating pressures directly to the gums in the mouth and the anterior parts transmits masticating pressures to the gums substantially only through said posterior parts.
  9. A sectionalized lower denture comprising right and left hand posterior denture parts, carrying posterior teeth and an anterior denture part carrying anterior teeth disposed between said posterior parts and constituting therewith a full artificial lower denture, the meeting ends of said posterior and anterior parts being on inclined planes with the anterior part having wedge-like action therebetween.
  80. 10. A sectionalized lower denture comprising right and left hand posterior denture parts, carrying posterior teeth and an anterior denture part carrying anterior teeth disposed between said posterior parts and constituting therewith a full artificial lower denture, the meeting ends of said posterior and anterior parts being on inclined planes, with the anterior part having wedge-like action therebetween, the parts being so formed that the anterior part is carried by said posterior parts.
  85. 11. A sectionalized lower denture comprising a plurality of denture parts constituting a full lower denture and means on the adjacent ends of said denture parts for joining said parts together, said joining means constituting cooperating dowel means at the adjacent ends of said parts.
  90. 12. A sectionalized lower denture comprising a plurality of denture parts, constituting a full artificial lower denture, means on the adjacent ends of said denture parts for joining said parts together, said joining means constituting a dowel pin and dove-tail tenon means on one part and dowel and dove-tail socket means on the other parts.
  95. 13. A sectionalized lower denture comprising a plurality of tooth carrying denture parts joined for relative movement and constituting a full lower denture, said parts having bases abutting endwise at an angle and one of said parts being disposed and constituting a wedge between the other parts.
  100. 14. A sectionalized lower denture comprising right and left hand posterior denture parts carrying posterior teeth, and an anterior denture part carrying anterior teeth disposed between said posterior parts and constituting therewith a full artificial lower denture, the meeting ends of said posterior and anterior parts being on inclined planes with the anterior part, said anterior part having wedge-like action between said posterior parts thereby permitting self-adjustable relative movement.
  105. 15. A dental plate comprising an intermediate section and a pair of end sections, said sections disposed in end to end abutting engagement with each other and the abutting ends of said sections being provided with complementary dove tail grooves to connect said sections together for relative sliding movement in a plane transverse to the occlusal plane of the denture, the sections constituting a complete or full denture.
  110. 16. A dental plate comprising a plurality of sections arranged in end to end abutting engagement with each other, and coacting means on the abutting ends of the sections for connecting said sections together for relative sliding movement in a plane transverse to the occlusal plane of the denture, said sections constituting a complete or full denture.

CHARLES H. WHARTON.
